PROCESS FOR TREATING ACID SLUDGES

Filed Jan. 28, 1929

UNITED STATES PATENT OFFICE

DAVID R. MERRILL, OF LONG BEACH, AND PHILIP S. CLARKE, OF BERKELEY, CALIFORNIA, ASSIGNORS TO UNION OIL COMPANY OF CALIFORNIA, OF LOS ANGELES, CALIFORNIA, A CORPORATION OF CALIFORNIA

PROCESS FOR TREATING ACID SLUDGES

Application filed January 28, 1929. Serial No. 335,626.

This invention relates to methods for the separation and recovery of sulfuric acid from acid sludges so that the acid may be concentrated for further use and the tarry portions 5 of the sludges may be employed as fuel.

Acid sludge obtained from the treatment of various petroleum oils consists of a large portion of sulfuric acid in intimate admixture with various organic compounds such as 10 sulfonated compounds, polymerized organic bodies and other reaction products, together with other substances which have been extracted from the petroleum distillates. As the sulfuric acid has been commonly recovered heretofore it has frequently possessed 15 too low a purity to permit concentration for re-use because of the presence of excessive quantities of carbonaceous impurities which cause the decomposition of excessive quantities of sulfuric acid during concentration. A further objection resides in the fact that sludges produced in the sulfuric acid treatment of light oils such as gasoline, kerosene, and engine distillates obtained from petroleum 20 oils particularly asphaltic base or California crudes, emulsify spontaneously with water; this is a decided difference from the action of lubricating oil acid sludges which do not so emulsify. Due to such ready emulsification of light oil sludges of the above character separation of the acid from the tarry constituents cannot be made satisfactorily 25 by those washing processes which have been used for heavy oil sludges. It has therefore been the practice to run the light oil sludges to waste, or to burn them while still containing large amounts of sulfuric acid, a procedure involving both nuisance and waste.

It is the object of our invention to present 30 a process whereby light oil sludges may be satisfactorily treated for the economical recovery of the sulphuric acid from the tarry portions and to render such tarry portions available for fuel.

We have discovered that the emulsifiable 35 light oil acid sludges obtained from petroleum oils, such as light oil sludges from asphaltic base and California crudes, can be prevented from emulsifying by washing such light oil sludges with a liquor which already

contains a comparatively high percentage of sulfuric acid. We have also discovered that the emulsification of light oil sludges may be prevented by washing them in admixture with relatively large quantities of heavy oil 40 sludges, for example lubricating oil sludges, it being then unnecessary that the wash water initially contain acid even though the acid content of the sludges be low. In the first instance those organic compounds which are water-soluble and cause the emulsification, are prevented from dissolving in the aqueous phase by the high sulfuric acid content of the same, an effect apparent analogous to "salting out" in organic chemistry. Moreover, we 45 have found that when the wash water has previously been used to wash a heavy oil sludge, the organic impurities in the acid liquor, which impurities have been derived from the two kinds of sludge, react together to 50 form substances insoluble in the liquor, and a purification of the liquor is thus effected. This reaction is apparently a physical coagulation of colloidal substances of such different character that they are largely incompatible in the same solution. In those cases 55 where the heavy and light oil sludges have been previously washed (with strong acid liquor, for example), such washed sludges will be mixed before being given a second 60 wash to remove the greater portion of the residual acid. The reason for mixing these once-washed sludges is that the heavy oil sludge serves to dilute the emulsifying constituents of the light oil sludge to such extent that said constituents become inoperative. For this purpose a comparatively large 65 proportion of heavy oil sludge must be used. Three times as much heavy oil sludge as light oil sludge usually is required, and a greater 70 quantity may be employed if desired. The ratio of three-to-one is typical, but sludges occasionally are found where a two-to-one or a one-to-one ratio will meet the requirements. 75 Not only does the heavy oil sludge effect dilution of the light oil sludge to prevent emulsification of the latter, but the light oil sludge also acts to reduce the viscosity of the heavy oil sludge in order that it may be more readily handled.

We have found a convenient method of operation to reside in what may be termed a "counter-current" washing method, that is, washing a previously washed sludge or mixture of sludges of low acid content with water containing little or no acid, and using the resulting wash liquor to wash fresh batches of sludges of high acid content. This washing method is preferably worked out in order to treat the light oil sludges with the strongest possible wash liquor, and this may be accomplished with a counter-current process comprising washing a mixture of previously washed light oil and lubricating (heavy) oil sludges with water containing little or no acid, using the resulting wash liquor to wash a fresh lubricating (heavy) oil sludge, and then employing the resulting comparatively strong acid wash liquor to wash a fresh batch of light oil sludge. The liquor from the last mentioned wash may then be further treated to separate as much of its tarry content as possible, and subsequently concentrated.

Therefore, broadly stated, the invention resides in treating a light oil acid sludge to prevent emulsification thereof by admixing said light oil sludge with a large proportion (as above defined) of a heavy (lubricating) oil sludge and washing the mixture with water. The invention resides also in washing a light oil acid sludge with a strong acid liquor, preferably a liquor obtained from washing a heavy oil sludge. The invention also resides in the purification of liquors from the two types of sludges by heating a mixture of such liquors to cause impurities to separate. The invention resides further in combining these steps to obtain a highly acid liquor for final purification, and to obtain a sludge residue as free as possible from acid, and suitable for use as fuel. In operating this combination of steps according to a desirable form, previously washed heavy and light oil sludges are mixed together and then washed with fresh water preferably regulated in amount to produce a liquor of minimum density compatible with its causing the tarry material to float on it thus facilitating the mechanical operation of separating the tar and aqueous phases, employing such resulting liquor to wash a fresh batch of heavy acid sludge to produce a resultant wash liquor having a comparatively high acid content, and in turn employing the resultant strong liquor to wash a fresh batch of light oil sludge, the highly acid liquor from which may be further purified and concentrated. These once-washed acid sludges are then mixed and washed with fresh water as above indicated to commence a new cycle.

In the accompanying drawing a preferred method of operating the present invention is diagrammatically indicated. In this instance, an agitator A contains a heavy acid

sludge such as lubricating oil sludge to be treated, and an agitator A' contains a light oil acid sludge such as kerosene or gasoline sludge to be treated, the light oil sludge being one which would emulsify if treated with fresh water. A kettle 1 is employed to receive heavy oil acid sludge from the agitator A and a kettle 2 is employed to receive a washed or treated sludge from kettle 1. A third kettle 3 receives charges of light oil sludge from agitator A' and a kettle 4 receives acid liquor from the kettle 3, the washed sludge from the kettle 3 being passed to the kettle 2.

In operating the process, a batch of heavy oil sludge introduced into the kettle 1 from the agitator A is washed with a weak acid wash liquor obtained from a second wash of previously treated sludges as hereinafter more fully described. The heavy oil sludge normally has an acid content of 25 to 40% H_2SO_4 , but the concentration of this acid in the sludge on a tar-free basis is much higher, varying from 50 to 75% in most cases. The wash is accomplished by heating the mixture of sludge and acid liquor with open or closed steam coils, preferably open coils in order that the mixture may be agitated by the steam, carrying a temperature of around 240 to 260° F. and continuing such treatment for a time sufficient to accomplish satisfactory separation of the acid liquor from the tarry constituents. The temperature employed is sufficient to boil the solution and the time to accomplish the desired results may vary from 15 or 20 minutes to one or two hours, according to the materials being handled.

The strong wash liquor obtained from kettle 1 and containing approximately 40% H_2SO_4 and from 0.5% to 10% of carbon based on the weight of the acid in the liquor, is now employed to wash a fresh batch of light oil sludge introduced into the kettle 3 from the agitator A', such light oil sludge normally having an acidity of about 50% H_2SO_4 . The mixture of strong acid liquor and fresh light oil sludge in kettle 3 is given a treatment preferably with steam from open coils, similar to the treatment carried on in kettle 1, the temperature being maintained at about 240 to 260° F. in order to boil the solution and obtain good contact, and the time being sufficient to obtain a satisfactory separation of the emulsified tarry constituents from the sulfuric acid solution. In this instance also the time of treatment will vary from 15 to 20 minutes to one or two hours according as the materials treated vary. The cooking in the kettle 3 is sufficient to purify partially the resultant sulfuric acid liquor so that substantially all of the sludge separates out. The completeness of the treatment and of the separating operation is indicated by the formation of a clear, light-colored solution when

a sample of the separated acid liquor is poured into a large volume of water. Should a turbid solution develop it will be indicative of the necessity for longer treatment. The 5 resultant separated sulfuric acid solution should have an acidity of over 50% H_2SO_4 and may run as high as 65% H_2SO_4 and will have a carbon content of from 0.5 to 4% based on the acid content.

10 The partially purified strong sulfuric acid liquor so obtained in kettle 3 after a short period of settling is run into kettle 4 where it is boiled with closed steam coils at a temperature from 260 to 320° F. for the purpose 15 of converting the organic impurities in the acid into insoluble forms by the combined effect of the acid and the high temperature, so that being insoluble they will separate and rise to the surface. This re-cooking operation 20 is carried on for a time sufficient to accomplish the desired results as stated which ordinarily requires from three to five hours.

The finished sulfuric acid liquor resulting 25 from the cooking in the kettle 4 is then conducted to a concentration plant 5 where it is prepared for reuse.

Small amounts of tar and other insolubles 30 separated in the kettle 4, together with the once-washed light oil sludge from the kettle 3, are conducted into the second wash kettle 2 where they are mixed with the once-washed lubricating oil sludge from the kettle 1.

This mixture of the heavy and light oil 35 sludges is then treated with steam, preferably from open coils, at a temperature and for a time similar to the treating conditions maintained in kettle 1, in the presence of fresh water added in an amount carefully controlled so as to yield an acid liquor of sufficient density to float the washed sludge and thus facilitate mechanical separation. This 40 will ordinarily require an acidity in the acid liquor of about 20%. Since the sludge mixture contained in kettle 2 has an acid content of about 10% H_2SO_4 on a basis which includes the tar in making the calculation and the acid present has a considerably higher concentration on a tar-free basis, it is not difficult to obtain a 20% acid content in the 45 resulting wash liquor.

This dilute wash liquor is run into the kettle 1, and is that above described as being employed to wash a fresh batch of lubricating oil sludge. It contains from 1 to 30% of 50 carbon based on the acid content.

The twice-washed sludge discharged from kettle 2 is now in a condition for use as fuel, and normally contains less than 2% of sulfuric acid.

55 The above procedure may be variously modified within the scope of the invention as regards the choice of washing media and methods of purification of the acid liquor. For example the fresh lubricating oil sludge 60 may be washed with fresh water. This re-

sults frequently in the production of an acid liquor of low purity, but purification can be accomplished by heating around temperatures of 230 to 260° F. for from one to three hours in admixture with light oil acid 70 sludges or acid liquor derived from light oil acid sludges, the impurities from the two sludges reacting with each other to alter their dispersion characteristics and separating in insoluble form. Also when cooking light oil acid sludges, water may be used as a diluent but it is necessary to maintain the strength of the sulfuric acid in the mixture at a relatively high concentration in order to separate the tarry matters from the acid constituents 75 satisfactorily. The best results have been obtained when the strength of the acid in said mixture runs between 50 and 65% H_2SO_4 . Acid liquor separated in this fashion from light oil acid sludges may be purified by treatment in admixture with lubricating oil acid sludge or with acid liquor derived from such sludge, the treatment being carried on under heat at temperatures around 230 to 260° F. 80 The results and products will be substantially 85 the same as those obtained by the other modifications outlined above.

If desired the so-called "neutral skimmings" may also be run into the kettle 2 with the mixed sludges which are there given their second wash, the tarry contents thus being introduced into the twice-washed sludge taken off for fuel. These skimmings are obtained from the waste alkali liquor drawn from the agitators A, A' at other stages of treatment of the oil stocks, the skimmings being a mixture of oil and naphthenic and other organic acids precipitated in a neutralizing box 6 by acidification of said waste alkali liquor with some acid wash liquor diverted at any convenient point in the washing operations, for example from the line leading from kettle 1 or the line leading from kettle 2. In this manner the recovery of said "neutral skimmings" is conveniently accomplished.

The above descriptions are merely illustrative of the generic invention, and it is to be understood that many modifications may be made within the range of the accompanying claims by those skilled in the art.

We claim:

1. A method for treating acid sludges comprising washing a heavy oil sludge with a weak acid wash liquor, employing the resultant strong acid wash liquor to wash a light oil sludge which emulsifies when washed with fresh water, mixing the washed heavy and light oil sludges, washing such mixed sludges with fresh water, and employing the resultant weak wash liquor as the washing medium for a fresh batch of heavy oil sludge in a new cycle.

2. A method for treating acid sludges comprising mixing previously washed light and heavy oil sludges, washing such mixture

with water, employing the resultant acid liquor to wash a fresh heavy oil sludge, and employing a strong acid liquor from the last mentioned wash to wash a fresh batch of light oil sludges.

3. A method according to claim 2 wherein the strong acid liquor from the wash of the fresh light oil sludge is heated until impurities separate out, and recovering the resultant purified acid liquor.

4. A method for recovering acid from acid sludges obtained from the treatment of petroleum products, comprising mixing a heavy oil sludge with a light oil sludge, the light oil sludge being such that it would tend to emulsify if washed alone with fresh water, washing the sludge mixture with water at a temperature sufficient to boil the solution to cause separation of tarry constituents and washing a fresh batch of heavy oil sludge with the acid liquor from the first mentioned wash at a temperature sufficient to boil the solution for the separation of tarry constituents.

5. A method for recovering acid from acid sludges comprising washing a heavy oil sludge with a weak acid wash liquor at an elevated temperature to cause separation of tarry constituents from the resultant liquor, employing the resultant strong acid liquor to wash a light oil sludge which emulsifies when washed with fresh water, the washing of said light oil sludge with the strong acid liquor being carried on at a temperature to boil the solution and cause separation of tarry constituents, mixing the washed heavy and light oil sludges, washing such mixed sludges with fresh water, and employing the resultant weak wash liquor as a washing medium for a batch of heavy oil sludge in a new cycle.

6. A method for the separation of the constituents of acid sludges obtained from acid treatment of petroleum products, comprising washing a heavy oil sludge with a weak acid liquor at a temperature to boil the solution, employing the resultant strong acid liquor to wash a light oil sludge which would emulsify if washed with fresh water, the washing of the light oil sludge with the strong acid liquor being carried on at a temperature to boil the solution for the separation of tarry constituents, and heating the strong liquor from the washing of the light oil sludge at a temperature to boil the solution to separate impurities in insoluble form.

7. A method for recovering acid from acid sludges comprising washing a heavy oil sludge and obtaining a strong acid liquor therefrom, washing a light oil sludge with said acid liquor, the light oil sludge being inclined to emulsify if washed with fresh water, continuing the washing of the light oil sludge with said liquor at an elevated temperature to cause separation of the tarry constituents, and heating the strong acid liquor

from the wash of the light oil sludge to cause separation of impurities.

8. A method according to claim 7 wherein the washed heavy and light oil sludges are mixed and washed with water, and the resultant liquor is employed to wash the heavy oil sludge in a new cycle.

9. A method for recovering acid from acid sludges comprising treating with a strong acid wash liquor a light oil sludge having a tendency to emulsify when washed with fresh water, heating the solution during such treatment with acid liquor to cause separation of tarry constituents, and heating the acid liquor resulting from such treatment in admixture with acid liquor from the treatment of heavy oil sludges to cause separation of impurities from the mixed liquors.

10. A method for recovering acid from light oil sludges which tend to emulsify when treated with fresh water, comprising treating said sludges with a wash liquor sufficiently strong in acid to prevent emulsification, and heating the mixture at an elevated temperature to cause separation of tarry constituents from the liquor.

11. A method for recovering acid from light oil sludges which emulsify when treated with fresh water, comprising boiling the light oil sludge with a wash liquor containing acid sufficient to prevent emulsification, and continuing the boiling for separation of tarry constituents until a clear light-colored solution will form when a sample of the separated acid liquor is poured into a large volume of water.

12. A method of treating acid sludges which comprises mixing an acid sludge which emulsifies when washed with water with an acid sludge which will not emulsify when washed with water and washing the mixture with water.

13. A method for treating acid sludges comprising mixing an acid sludge which emulsifies when washed with water with an acid sludge which will not emulsify when washed with water, washing the mixture with water, and washing a fresh batch of non-emulsifying sludge with the acid liquor from the washing of the sludge mixture.

14. A method for treating acid sludges comprising employing a liquor to wash a mixture of previously washed sludges which respectively are emulsifying and non-emulsifying when washed with water, then washing a fresh batch of non-emulsifying sludge with the resulting liquor from said previous wash and then washing a fresh batch of emulsifying sludge with the resulting liquor from said wash of the non-emulsifying sludge.

15. A method for treating acid sludges comprising employing a liquor to wash a mixture of previously washed sludges which respectively are emulsifying and non-emulsifying when washed with water, then wash-

ing a fresh batch of non-emulsifying sludge with the resulting liquor from said previous wash, then washing a fresh batch of emulsifying sludge with the resulting liquor from said wash of the non-emulsifying sludge and boiling the resultant liquor to separate impurities therefrom.

16. A method for treating acid sludges from petroleum treating processes comprising mixing previously washed acid sludges in the proportion of at least one part of an oil sludge which will not emulsify when washed with water to one part of an oil sludge which emulsifies when washed with water and heating such mixture with water containing substantially no acid to obtain a separation of acid liquor from the mixed sludges.

17. A method for treating oil sludges which emulsify when washed with water and oil sludges which will not emulsify when washed with water comprising washing a mixture of such sludges and heating the liquor from said wash to cause the separation of impurities.

18. A method for treating oil sludges which emulsify when washed with water and oil sludges which will not emulsify when washed with water comprising washing a mixture of such sludges at a temperature approximately 240 to 260° F., and heating the liquor from said wash to cause the separation of impurities.

19. A method for treating acid sludges comprising mixing an acid sludge which emulsifies when washed with water with an acid sludge which will not emulsify when washed with water, washing the mixture with water, separating the acid liquor from the mixed sludges, increasing the acid content of the wash liquor so that the liquor is sufficiently strong in acid to prevent emulsification of a fresh batch of emulsifying sludge, and washing a fresh batch of such emulsifying sludge with such acid liquor.
